A. H. GIBSON

SOUND REPRODUCING AMPLIFIER

Filed June 2, 1926

UNITED STATES PATENT OFFICE.

ANGUS H. GIBSON, OF SALT LAKE CITY, UTAH, ASSIGNOR TO AMERICAN RADIO PRODUCTS COMPANY, OF SALT LAKE CITY, UTAH, A CORPORATION OF UTAH.

SOUND-REPRODUCING AMPLIFIER.

Application filed June 2, 1926. Serial No. 113,250.

This invention relates to sound-reproducing amplifiers for use with radio-receiving apparatus, and is intended to provide a device of that class which shall reproduce in full, loud tones the original sounds transmitted electrically to the apparatus without the usual loss of distinctness or clearness due to distortion of the reproducing device. In practice it has generally been found that with increasing loudness in the sounds reproduced by radio transmission there is a loss of distinctness or clearness due to distortion of vibration in the reproducing device.

This invention deals with that problem and is intended to provide a device of that class which shall reproduce in loud tones the original sounds transmitted electrically without the usual loss of distinctness or clearness.

To this end the invention comprises, generally speaking, in combination with a magnet and an associated induction coil, an armature plate arranged interiorly of the coil and transversely of its windings with its projecting ends in close proximity to the magnet poles, said armature plate being fulcrumed in said coils by non-vibratory cushioning means so as to prevent distortion of the vibration set up in the plate by the inductive action of the electrical waves or undulations in the coil current, while not interfering with the desired freedom of vibration, combined with a sound-reproducing diaphragm having vibration transmitting connection with the armature plate. This and other features of the invention will be described in the following specification and will be defined in the claims hereto annexed.

In the accompanying drawings I have illustrated such details of construction and arrangement as are necessary to a complete understanding of my aforesaid improvement, in which:

Figure 1 is an elevation, partly in vertical section, showing an assemblage of parts embodying the present invention.

Figure 2 is a front elevation of the same in a plane at right angles to the plane of Figure 1.

Figure 3 is a plan view of the cover or lid of the sound box partly removed to show the reproducing diaphragm.

Figures 4 and 5 are, respectively, trans-

verse and longitudinal sections of the armature plate mounted in the induction coil.

Figure 6 is a plan view of the armature plate with one form of cushioning support,

Figures 7 and 8 show, respectively, in plan and in cross section, another arrangement for the cushioning support of the armature plate.

Figures 9 and 10 are similar views of another modification of the armature plate.

In the practice of the invention, according to the specific embodiment thereof illustrated in the drawings, I employ a permanent magnet 1, whose poles, in this instance, are provided with inwardly projecting extensions 2 and 3, which are forked or grooved to sub-divide each pole of the magnet into parallel branches, whose ends are in juxtaposition to the ends of the branches of the opposite pole.

In the space formed by these grooves in the opposing poles is mounted a spool 4, having a hollow or flat tubular core, and carrying a considerable length of fine insulated wire coil 5, forming an induction coil 80 in circuit with the reproducing circuit of the receiving set. This spool 4 is arranged with its central opening or hollow core in alignment with the space separating the opposite poles of the magnet.

Within this hollow core of the induction coil and spool 4, 5, is mounted a transverse plate 6 of magnetizable material, such as soft iron or the like, with its opposite ends projecting through the coil and in close proximity to the poles of the magnet.

The mounting of this armature plate inside the coil is of the utmost importance. At this point, my improvement consists in providing such a support for the armature plate that it is held thereby in proper relation to the coil and the magnet poles, while at the same time its vibration, due to the inductive action of the undulations or waves in the current of the coil 5, shall not be 100 distorted or marred by the supporting connection. There are several forms of such supporting connection illustrated in the drawings but all embrace the use of an elastic support that will not transmit vibration and yet will allow complete freedom of vibration in the armature plate.

In the forms shown in Figures 4, 5 and 6 the armature plate 6 is provided with a row of spaced perforations through which 110

is drawn a strip of soft or elastic vulcanized rubber which is threaded through from one side to the other so as to space the plate equally between both walls of the core of 5 the coil and between the opposite poles of the magnet. Polarization of the magnet plate will, of course, be transverse to the windings of the induction coil, or in the direction of the axis of the coil, so that one 10 projecting end of the magnet plate becomes a north pole and the other a south pole with the rubber strip forming an elastic support or buffer normally holding the armature plate in its correct medial position, while 15 allowing the plate to vibrate according to the nature of the undulations or waves in the current passing through the induction coil.

At one end, preferably for convenience 20 the inner end, of the plate 6, there is secured a rod or wire 8, which is carried up and firmly secured to diaphragm 9, as shown at 8^b, in order to transmit the vibration of the plate 6 to the diaphragm 9 and thereby 25 reproduce sound waves corresponding to those originally transmitted by electrical waves to the apparatus. The joints at 8^a and 8^b, with the armature plate and the diaphragm respectively, should be tight and 30 free from rattle and may be made either by soldering or mechanical connection. The sound box comprises a bottom member 10 and a top or cap 10^a, provided with a central opening 10^b for the escape of the 35 sound waves and for the insertion of a loud-speaking horn if desired. The two members of the sound box are secured together in any convenient fashion, as by screws, so as to clamp the peripheral or 40 edge portion of the diaphragm between them with a circular space intervening between each face of the diaphragm and the adjacent 45 face of the sound box members. The vibration transmitting rod or wire 8 is preferably carried up through a hole in one arm 50 of the magnet, according to the arrangement illustrated, in order to make the apparatus as compact as possible.

It will be observed that around the vibration-transmitting rod 8 is a rubber sleeve 55 extending from the armature plate to the diaphragm. The object of this sleeve is to prevent excessive amplitude of vibration on the part of the relatively large diaphragm 65 by interposing a non-vibratory buffer or damper which will not interfere with its normal vibration, but tends to prevent excessive rebound.

In Figures 7 and 8 I have shown a modified 60 construction for supporting and cushioning the armature plate. In this case the armature plate, instead of being perforated, is notched midway of its opposite side edges and an elastic band 7^a of rubber is stretched 65 over the plate to seat in these notches so as

to form a transverse elastic fulcrum for the plate corresponding in function to the strip 7, above described.

In Figures 9 and 10 the plate 6^b is shown with two spaced perforations midway of the plate in which are inserted soft rubber buttons 7^b forming an elastic fulcrum or support.

The preferred form of diaphragm has its central portion slightly bowed or cupped and 75 the surrounding portion formed with annular concentric corrugations or waves to secure greater responsiveness to the transmitted vibrations. The armature plate is located in position of maximum responsiveness to the inductive action of the coil and also to the action of the magnet poles, while at the same time with its elastic non-vibratory support there is no loss or distortion of vibration by transmission through any supporting means. The elastic cushion tends to support the diaphragm in position and to yieldingly oppose movement of the diaphragm away from its medial position as well as restoration to such position when it is moved ever so slightly away from it.

What I claim is:

1. In a sound reproducing amplifier the combination with a magnet, of an induction coil located between the poles of the magnet 95 and having a hollow core, an armature plate inserted in said core, a soft rubber band encircling the middle portion of said plate transversely thereof, and forming a medial fulcrum support for said armature plate, the ends of said plate projecting axially of the coil into juxtaposition with the respective poles of the magnet, a sound reproducing diaphragm and a metallic rod secured to one end of said plate and to the diaphragm to 105 conduct vibration of the plate to the diaphragm.

2. A sound reproducing device embracing in combination an induction coil having a hollow core, an armature plate mounted inside said hollow core upon an elastic non-vibratory cushion with its ends projecting beyond the sides of the coil, a magnet between whose poles said coil is placed in position to locate the ends of the plate in close proximity to but out of contact with said armature plate, a sound-reproducing diaphragm and means for transmitting vibrations of the armature to said diaphragm, and means for preventing excessive amplitude of vibration in the diaphragm 120 interposed between the diaphragm and the armature.

3. In a sound reproducing amplifier the combination with an induction coil having a hollow core and an armature plate inserted transversely through said core and yieldingly fulcrumed therein at its medial point but out of contact therewith by vibration insulating supporting means tending to 125

hold it in medial position, while allowing it freedom of vibration in response to undulation in the electric current passing through said coil.

5. 4. In a sound reproducing amplifier, the combination with a sound-reproducing diaphragm, of an armature plate mounted inside an induction coil within the field of the poles of a magnet so as to be set in vibration by the joint inductive action of the magnet and of the current passing through the coil, a rod connecting one end of the plate to said diaphragm to transmit vibration of the plate, and a cushioning sleeve around said rod interposing a cushioning resistance between the plate and the diaphragm.

5. A sound-reproducing amplifier embracing in combination with a magnet, an associated induction coil wound around a hollow core, an armature member inserted through said core transversely of the coil with its ends disposed within the magnetic range of the poles of the magnet, a fulcral support of vibration insulating material engaging opposite sides of the medial portion of the armature, a sound-reproducing diaphragm and means for transmitting magnetically induced vibrations of the armature to said diaphragm.

In witness whereof, I have subscribed the above specification.

ANGUS H. GIBSON.
